UNITED STATES PATENT OFFICE.

SUSANNA COCROFT, OF NEW YORK, N. Y.

ELECTRIC HAIR WAVER.

Application filed August 28, 1926. Serial No. 132,177.

This invention relates to an electrically heated hair waver and has for its object to provide, in a manner as hereinafter set forth, a device of such class for imparting to the hair a permanent wave like a Marcel instead of the round curl effect, or a kink effect, which is given to the hair by the present types of permanent wavers now employed.

A further object of the invention is to provide, in a manner as hereinafter set forth, a device of the class referred to including a wave-forming member free of permanent connection and associated with a heater element to provide in connection therewith the wave, and with said member capable of being positioned upon the head, independent of the heater element, to receive the strand of hair to be waved and then held in detachable inter-engagement with the heater element, by the latter, to form a permanent wave like a marcel and free of distinct round curves or kinks.

A further object of the invention is to provide, in a manner as hereinafter set forth, a device of the class described for individual or home use.

A further object of the invention is to provide, in a manner as hereinafter set forth, an electrical hair waver device including a hair waving member for receiving the strand of hair to be waved and free of connection with the heater element of the device, thereby permitting of such member being arranged in hair receiving position on the head without the inconvenience of handling the heater element during such step, and further providing the heater element with means coacting with said wave member and further with means for detachably coupling said member to the heater element, after said member has been positioned in hair receiving position, whereby the strand of hair will be provided with a permanent wave like a marcel and with said wave free of distinct curves, curves or kinks.

Further objects of the invention are to provide, in a manner as hereinafter set forth, an electrical hair waver which is simple in its construction and arrangement, strong, durable, compact, for individual use, thoroughly efficient, conveniently handled, expeditious in its action to produce a wave effect upon the hair, and comparatively inexpensive to manufacture.

With the foregoing and other objects in view, the invention consists of the novel con-

struction, combination and arrangement of parts as hereinabove more specifically described, and illustrated in the accompanying drawings, wherein is shown an embodiment of the invention, but it is to be understood that changes, variations and modifications can be resorted to which fall within the scope of the claims hereunto appended.

In the drawings, wherein like reference characters denote corresponding parts throughout the several views:

Figure 1 is a top plan of an electrical hair waver in accordance with this invention and illustrating the same in operative position with respect to a strand of hair to be waved.

Figure 2 is a vertical sectional view of an electrical hair waver in accordance with this invention.

Figure 3 is a section on line 3-3 of Figure 1.

Figure 4 is a perspective view of the hair waving member and showing the position thereof with respect to a pair of flexible combined hair protecting and dampening elements formed of fabric and which has the strand of hair, to be waved, positioned therebetween.

Referring to the drawings in detail, an electrical hair waver, in accordance with this invention, comprises a handle 1 which has extended from one end thereof an electric heater element, referred to generally by the reference character 2. Circuit wire connections, indicated at 3 extend through the handle 1 and connected to the element 2. The handle 1 is provided with a switch 4 for opening and closing the circuit of the heater element 2. The heater element 2 is joined with the handle 1 by what may be termed a neck portion 5 which is slotted to provide an opening 6 and with the material freed by the slit extended to form a pair of lugs 7 for a purpose to be presently referred to. Extending through the opening 6 and positioned between the lugs 7, as well as being pivotally connected with the latter, as at 8, is a clamping lever, referred to generally by the reference character 9 and which is set up with an inclined intermediate portion 10, a forward slightly curved clamping portion 11 and a rear or handle portion 12 which is arranged in opposed relation with respect to the handle 1. The function of the clamping lever 9 will be presently referred to.

With reference to Figure 3, the heater element 2 consists of a body portion comprising an upper curved part 13 and a pair of

lower curved parts 14, 15 which are oppositely disposed with respect to the curved part 13. The part 13 is on a materially greater arc than either part 14 or 15 and the parts 14 and 15 are upon the same arc with respect to each other. Depending from the curved part 13 is a pair of outwardly inclined parts 16, 17 which are oppositely disposed with respect to each other and the part 16 merges 15 into the inner side of the part 14 and the part 17 merges into the inner side of the part 15. The parts 13, 16 and 17 form the heater with an inverted U-shaped portion having its sides flaring with respect to each other. Extending 20 upwardly from the parts 14, 15 is a pair of inclined parts 18, 19 which are outwardly inclined and the part 18 extends from the outer side of the part 14 and the part 19 extends from the outer side of the part 15. When 25 the heater element is in normal position, that is to say in superposed relation with respect to the wave-forming member, to be presently referred to, the said parts 13, 15 and 17 provide the heater element with the inverted U-shaped portion as referred to and the said parts 14, 16 and 18 provide the heater element with a V-shaped portion and the said parts 15, 17 and 19 also form the heater element with a V-shaped portion. The V-shaped portions provide the heater element with a pair of upwardly opening channels and the U-shaped portion forms the heater element with a downwardly opening channel. When the heater element is arranged in superposed relation with the wave-forming member, to be hereinafter referred to, as well as in cooperative relation therewith, the said wave-forming member extends into the spaces formed by the inverted U-shaped 35 portion and the pair of V-shaped portions. The V-shaped portions are oppositely disposed with respect to the U-shaped portions. The part 18, as well as the part 19, at its top terminates in a right-angularly disposed flange and the flange which extends from the part 18 is indicated at 20 and the flange which extends from the part 19 is indicated at 21. In Figure 3 the heater element is illustrated in cross section and reversed from 40 normal position.

The wave-forming member is referred to generally by the reference character 22 and is constructed from a plate of the desired gauge and preferably sheet metal. The wave-forming member 22 is shaped to provide a pair of outer and an intermediate U-shaped portion. The intermediate U-shaped portion is oppositely disposed with respect to the outer U-shaped portions. The outer U-shaped portions are indicated at 23, 24 and the intermediate U-shaped portion at 25. The U-shaped portions provide the wave-forming member with a pair of upwardly opening channels and a downwardly opening channel. The intermediate U-

shaped portion 25 is adapted to extend in the inverted U-shaped portion of the heater element and the outer U-shaped portions 23, 24 are adapted to receive the V-shaped portions of the heater element. The outer leg 70 of the outer U-shaped portion 23 of the wave-forming member 22, terminates in a right angularly disposed flange 26 adapted to oppose the flange 20 and the outer leg of the U-shaped portion 24 terminates in a right 75 angularly disposed flange 27 which is adapted to compose the flange 21. The flanges 26 and 27 may be provided with openings 28 for the purpose of connecting therewith a clamp detachably securing therewith the protecting members to be presently referred to. 80

In normal position, that is to say when the wave-forming member 22 is employed, the portion 25 thereof is of inverted U-shape. The outer face of the portion 25, at the base 85 thereof, has secured thereto a handle piece 29 for said member 22, whereby the latter can be held by the individual when positioning the strand of hair relative to the member 22 and prior to the clamping of said member 22, detachably, in operative position, with respect to the heater element 2, by the clamping or holding lever 9. When positioning the wave-forming member 22 upon the head to receive the strand of hair to be 95 waved, the said member 22 is free of connection in any manner with the heater element 2.

The strand of hair, which is indicated at 30 is adapted to be positioned between a pair 100 of combined protecting and moistening elements or members 31, 32, formed of suitable fabric and which are interposed between the element 2 and member 22 and are of less width than said member 22 and element 2 but of greater length. During the waving operation the strand of hair 30 is confined between the members 31 and 32. Preferably the members 31 and 32 are formed of a short length of flannel. The members 31 and 32 are soaked with a suitable liquid composition and which, when the heater is applied, gives the permanent wave. This is attained by emulsifying the oil in the hair and by a slight stretch which elongates the cells, making them pliable. 110

The member 22 is positioned upon the head and held by the handle piece 29, the member 31 which has been impregnated with the liquid composition, is positioned upon the upper face of the member 22, the strand of hair 30, which is to be waved, is placed upon the upper face of the member 31, and after which the member 32, which has been impregnated with the composition or preparation, is placed upon the hair 30. The member 22 is still held on the head by the handle piece 29, due to the fact that the individual has grasped said handle piece. After the elements 22, 31, 30 and 32 have been arranged 115 120 125 130

in the position as stated, the holding or clamping lever 9 is opened so that the portion 11 thereof can be slid within the intermediate U-shaped portion 25 of the member 22, the heater element 2 is then positioned over the member 32, and the clamping lever 9 now actuated, which provides for the clamping of the element 2, 22, 31, 30 and 32 together so that the said elements 10 will be held in interengagement with respect to each other. After the said elements have been clamped in an interengaging position with respect to each other, the heat is then turned on for a period of seven 15 minutes. After the duration of such time the elements 2, 22, 31 and 32 are removed from the strand of hair 30 and the same will be provided with a permanent wave, like a Marcel wave, and with the wave set up to 20 be free of distinct curves or kinks. The manner of operating the device is the same substantially as that of other individual permanent wavers or curlers only it gives the wave like a marcel instead of a curl. It does not 25 give a kink and the tendency is to set itself after washing in the same way in which it is waved without being obliged to be water waved after each shampoo.

It is thought that the many advantages of 30 an electrical hair waver, in accordance with this invention can be readily understood, and although the preferred embodiment of the invention is as illustrated and described, yet it is to be understood that changes in 35 the details of construction can be had which fall within the scope of the invention as claimed.

What I claim is:

1. An electric hair waver comprising an 40 electric heater element of corrugated contour, a handle extended from one end thereof, a clamping lever pivotally connected with said element and having a portion thereof arranged below said element, and a corrugated wave forming member coacting with said element, free of connection with said lever and detachably clamped in interengaging position with respect to said element by the said portion of said lever.

2. An electric hair waver comprising an 50 electric heater element of corrugated contour, a handle extended from one end thereof, a clamping lever pivotally connected with said element and having a portion thereof arranged below said element, a corrugated wave-forming member coacting with said element, free of connection with said lever and detachably clamped in interengaging position with respect to said element by the said portion of said lever, and a handle piece carried by said member and independent of said element.

3. An electric hair waver comprising an 60 electric heater element of corrugated contour, a handle extended from one end thereof, a

clamping lever pivotally connected with said element and having a portion thereof arranged below said element, a corrugated wave forming member coacting with said element, free of connection with said lever and detachably clamped in interengaging position with respect to said element by the said portion of said lever, said element and said member provided with oppositely extending lateral flanges, the flanges of said element adapted to be arranged in superposed position with respect to the flanges of said member when said member and element are in interengaging position.

4. An electric hair waver comprising an 70 electric heater element of corrugated contour, a handle extended from one end thereof, a clamping lever pivotally connected with said element and having a portion thereof arranged below said element, a corrugated wave-forming member coacting with said element, free of connection with said lever and detachably clamped in interengaging position with respect to said element by the said portion of said lever, a handle piece carried by said member and independent of said element and member provided with oppositely disposed lateral flanges, the flanges of said element arranged in superposed relation with respect to the flanges of said member when said element and member are in interengaging position.

5. An electrical hair waver comprising an 80 electrical heater element normally in an open circuit and of corrugated contour, a handle extended from said element and provided with means for opening and closing the circuit therefor, a corrugated wave forming member coacting with said heater element and adapted to be arranged therewith, flexible hair protecting elements interposed between said heater element and said member, and a 85 clamping lever pivotally connected to said heater element and having a portion adapted to extend below said member and free of connection with the latter and providing means for detachably clamping the said elements 90 and member in interengaging position to wave the hair when said circuit is closed.

6. An electric hair waver comprising a 95 combined electric heater and hair waving element, a hair waving member coacting therewith, and means free of connection with said member and carried by said element for detachably maintaining said member and element in hair waving position.

7. An electric hair waver comprising a 105 combined electric heater and hair waving element, a hair waving member coacting therewith, and means free of connection with said member and carried by said element for detachably maintaining said mem- 110

- ber and element in hair waving position, and a handle piece carried by said member and independent of said element. 65
8. An electric hair waver comprising a combined electric heater and hair waving element of corrugated contour, a hair waving member coacting therewith and of corrugated contour, and a clamping lever free of connection with said member, pivotally carried by said element and providing means for detachably maintaining said member and element in hair-waving position. 70
9. An electric hair waver comprising a combined electric heater and hair waving element of corrugated contour, and formed with a pair of oppositely disposed laterally extending flanges, a hair waving member coacting with said element and of corrugated contour and provided with oppositely disposed laterally extending flanges adapted to oppose the flanges of said element, and means free of connection with said member and carried by said element for detachably maintaining said member and element in hair waving position. 75
10. An electric hair waver comprising a combined electric heater and hair waving element of corrugated contour and provided with oppositely disposed laterally extending flanges, a hair waving member coacting with said element and of corrugated contour and provided with laterally extending oppositely disposed flanges adapted to oppose the flanges of said element, and a clamping lever pivotally connected to said element, free of connection with said member and providing means for detachably maintaining said member and element in hair waving position. 80
11. An electric hair waver comprising a combined electric heater and hair waving element of corrugated contour and provided with oppositely disposed laterally extending flanges, a hair waving member coacting with said element and of corrugated contour and provided with oppositely disposed laterally extending flanges adapted to oppose the flanges of said element, a clamping lever pivotally carried by said element and free of connection with said member and providing means for maintaining said member and element in hair waving position and with said member detachably engaging in said element, a handle piece carried by said member and independent of said element, and a handle carried by said element and independent of said member. 85
12. In an electric hair waver having as a part thereof an electric heater, a hair waving member of corrugated contour and provided with a pair of oppositely disposed laterally extending flanges, and a handle piece carried by said member and independ- 90
- ent of the heater and further free of connection with the latter. 95
13. In an electrical hair waver, a pair of interengageable hair waver members normally clear of each other, means to provide for the electrical heating of one of said members, a pair of flexible, combined hair protecting and moistening elements interposed between said members and between which the hair to be curled is positioned, said elements shiftable into said waver members when the latter are moved to interengaged position, and means carried by one of said members and abutting against the other of said members for moving one of said members relatively to the other to provide for the interengagement of such members. 100
14. In a hair waver, a channelled electrically heated hair channeled waving member, a channelled hair waving member adapted to cooperate with said electrically heated member, and independent moistening elements of fabric positioned against the inner faces of said members. 105
15. In a hair waver, a pair of combined hair protecting and moistening elements for positioning between a pair of channeled hair waving members, each of said elements formed from a strip of fabric capable of conforming to the contour of the inner face of each of said members during the hair waving operation. 110
16. In an electric hair waver a pair of interengageable hair waver members normally clear of each other, said members being channelled and of like contour and oppositely disposed relative to each other, one of said members provided with means to electrically heat it, and means carried by one of said members and abutting against the other of said members for moving one of said members relatively to the other to provide for the interengagement of such members. 115
17. In an electric hair waver a pair of interengageable hair wavers normally clear of each other, said members being channelled and of like contour and oppositely disposed relative to each other, one of said members provided with means to electrically heat it, means carried by one of said members and abutting against the other of said members for moving one of said members relatively to the other to provide for the interengagement of such members, and a pair of independent, flexible, combined hair protecting and moistening elements interposed between said members and between which the hair to be curled is positioned. 120

In testimony whereof, I hereby affix my signature.

SUSANNA COCROFT.
